Attorney

UNITED STATES PATENT OFFICE.

GOTTFRIED SCHICK, OF TAMPA, KANSAS.

FEEDING MECHANISM.

Original application filed October 29, 1921, Serial No. 511,317. Divided and this application filed June 24, 1922. Serial No. 570,673.

To all whom it may concern:

Be it known that GOTTFRIED SCHICK, a citizen of the United States, residing at Tampa, in the county of Marion and State 5 of Kansas, has invented certain new and useful Improvements in Feeding Mechanisms, of which the following is a specification, reference being had to the accompanying drawings.

10 This invention relates to certain improvements in feeding mechanisms and has relation more particularly to a mechanism of this general character especially designed and adapted for use in connection with fanning mills of a type disclosed in my pending application, Serial No. 511,317, of which the present application is a division and it is an object of the invention to provide a feeding member supported by the chute or the like 15 for movement toward or from said chute together with means for constantly urging said member toward the chute or more particularly the bottom thereof.

Furthermore, it is an object of the invention to provide a feeding mechanism including an agitating means associated with the discharge opening, said means serving as a 20 guard.

The invention consists in the details of 25 construction and in the combination and arrangement of the several parts of my improved feeding mechanism whereby certain important advantages are attained and the device rendered simpler, less expensive and 30 otherwise more convenient and advantageous for use, as will be hereinafter more fully set forth.

The novel features of my invention will 35 hereinafter be definitely claimed.

40 In order that my invention may be better understood, I now proceed to describe the same with reference to the accompanying drawings, wherein:

Figure 1 is a fragmentary view in side elevation illustrating a fanning mill with 45 which is associated the feeding mechanism constructed in accordance with an embodiment of my invention;

Figure 2 is a fragmentary longitudinal 50 vertical sectional view taken through the construction illustrated in Figure 1 but in reverse arrangement;

Figure 3 is a fragmentary view partly in 55 section and partly in elevation illustrating the portion of the means for driving the rotatable feeding member;

Figure 4 is a fragmentary view partly in vertical section and partly in elevation illustrating the rotatable feeding member and the associated agitating means; 60

Figure 5 is a fragmentary view partly in side elevation and partly in section illustrating certain features of the rotatable feeding member; and

Figure 6 is a fragmentary view in perspective of the agitating member and guard.

As disclosed in the accompanying drawings, H denotes a housing of requisite dimensions which is provided at one end with a casing 1 for the fan F. The fan F includes a shaft 2 adapted to be driven in any desired manner and which has fixed to an end portion thereof a pulley 72 with which is operatively engaged an endless belt 71. The belt 71 passes over and in driving engagement with a pulley 45. The pulley 45 is fixed to an end portion of the shaft 48 rotatably supported by and extending through a side wall 3 of the housing H. This shaft 48 extends inwardly of the housing H 70 and to said inner end portion is fixed a pinion 49 which, when the hopper A is in applied position meshes with a pinion 50 fixed to an extended end portion of a shaft 24 so that as the pulley 45 is rotated the 75 shaft 24 will be driven.

The hopper A is supported by the beams or members 6 and 8 extending transversely of the housing H, said hopper being substantially V-shaped in section in a direction 80 lengthwise of the housing H. The center portion of the forward wall 10 of the applied hopper at the bottom thereof is provided with a discharge opening 11 opening into the downwardly and forwardly inclined 85 chute C, said chute including the upstanding side walls 12. Co-acting with the discharge opening 11 of the hopper A is a slide valve 14 providing means whereby the flow of the grain through said opening 11 may 90 be regulated or controlled.

The valve 14 is provided with an upstanding extension 15 slidably engaged within a guideway 16. The outer or free end portion of said extension 15 carries a rack 17 disposed longitudinally thereof and with which meshes a pinion 18. The pinion 18 is fixed to a shaft 19 rotatably supported by the suitably spaced bearings 20 and said shaft is provided with an angularly disposed extension or arm 21 providing an operating member whereby the shaft 19 may be rocked 105 110

in a direction to impart the desired movement to the valve 14.

Also co-acting with the rack 17 is a resilient dog or pawl 22 whereby the valve 14 is held in its different adjusted positions. This dog or pawl, however, offers no resistance or obstruction to the desired movement of the valve 14 upon rocking or partial rotation of the shaft 19.

10 The side walls 12 of the chute C at a point in close proximity to the hopper A are provided with the transversely aligned open and arcuate slots 23 which are adapted to receive the opposite end portions of a shaft 24 extending outwardly of said side members 12 and adapted to be driven in a manner to be hereinafter more particularly referred to. Carried by the shaft 24 and substantially bridging the space between the 20 side walls or members 12 are the blades 25 which, as the shaft 24 rotates, serve as a feeder to facilitate the flow of the grain along the chute C.

Connecting the upper marginal portions of 25 the side members or walls 12 of the chute C forwardly of the shaft 24 and the feeding blades 25 carried thereby is a cross member 26. Pivotedly engaged with said cross member 26 are the oppositely directed arms 30 27, the pivotal mountings 28 for said arms being inwardly of the inner ends thereof. The inner ends of said arms 27 are provided with the intermeshing teeth 29 whereby said arms are caused to rock in unison and in the 35 same direction.

40 The outer end portions of the arms 27 extend outwardly of the side walls or members 12 and operatively engaged with said extended portions of the arms 27 and the extended portions of the shaft 24 are the links 30. Co-acting with one extended portion of the shaft 24 is a spring element 31 which serves to constantly urge the shaft 24 inwardly of the slots 23.

45 In the event any foreign substance should pass through the discharge opening 11 of a size or character to interfere with the requisite rotation of the blades 25, the shaft 24 will move outwardly without interfering with the desired rotation thereof. The curvature of the slots 23 is such that as the shaft 24 is moved outwardly, the same will be lifted upwardly so that the blades 25 will be raised a distance sufficient to permit said 50 foreign substance to pass therebelow. As soon as this substance or obstruction has passed the blades 25, the spring element 31 will operate to effect an automatic return of the shaft 24 to its normal position at the 55 inner or closed ends of the slots 23.

Pivoted substantially midway its ends, as at 33, to the rear wall 34 of the applied hopper A is an elongated arm or rod 35, the lower end portion of which has affixed thereto a cross head 36. The cross head 36 is in

relatively close proximity to the discharge opening 11 and has extending outwardly therefrom on an incline toward the forward wall 10 of the hopper A the tines 37, said tines being of a length to terminate at a 70 point close to the forward wall 10 above the opening 11. The end tines 37 at their central portions are formed to provide downwardly disposed extensions or arms 38 while the central tines 37 are formed to provide the upwardly extending arms 39. These tines 37 and the depending arms 38 provide a shield or guard to minimize the passage of foreign substances or obstructions passing through the opening 11 and 80 said tines 37, together with the arms 38 and 39, also provide means to agitate the grain immediately adjacent the opening 3 to facilitate the discharge of said grain through 85 said opening.

85 The agitating function of the tines 37 is accomplished upon rocking movement of the arm or rod 35 and, as herein disclosed, the upper end portion of said arm or rod 35 is provided with an angular extension 40 which 90 is disposed through a slot 41 in the rear wall 34 of the hopper A.

95 Operatively engaged with the portion of this extension 40 exteriorly of the hopper A is an end portion of a rod 42, said rod extending transversely of the housing H and having its opposite end portion operatively engaged with the free end portion of an arm a of a bell crank lever 43. The free end portion of the second arm b of this 100 lever 43 has operatively engaged therewith an end portion of a rod 44.

105 The opposite end portion of the rod 44 is operatively engaged with a pulley 45 so that, as the pulley 45 is rotated, the resultant 110 swinging movement of the bell crank lever 43 will reciprocate the rod 42 whereby the arm or rod 35 is rocked, resulting in the desired functioning of the tines 37 and the arms 38 and 39 carried thereby.

115 In order that the grain within the hopper will offer no obstruction to the desired rocking movement of the arm or rod 35, I enclose the same within a hood or casing 46 fixed to the rear wall 34 of the hopper A, 115 the lower face of said hood or casing 46 being open. The cross head 36 is immediately adjacent the open end of the hood or casing 46 and the top plate 47 of said hood or casing is extended to overlie said cross head. 120

125 The chute C, when the hopper is applied, discharges within an end portion of a cylinder S preferably supported and operated in the manner particularly set forth in my former application, Serial No. 511,317, hereinbefore referred to.

130 From the foregoing description it is thought to be obvious that a feeding mechanism constructed in accordance with my invention is particularly well adapted for use

by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A machine of the class described comprising a chute, said chute having side walls 15 provided with slots, a shaft seated within said slots, feeding means carried by the shaft and positioned within the chute, means for rotating the shaft, oppositely directed arms pivotally supported by the chute, the 20 inner extremities of said arms being provided with meshing teeth to cause said arms to rock in unison and in the same direction, and links connecting the outer portions of the arms and the shaft.
2. A machine of the class described comprising a chute, said chute having side walls provided with slots, a shaft seated within said slots, feeding means carried by the shaft and positioned within the chute, means 30 for rotating the shaft, oppositely directed arms pivotally supported by the chute, the inner extremities of said arms being provided with meshing teeth to cause said arms to rock in unison and in the same direction, 35 links connecting the outer portions of the arms and the shaft, said slots being disposed in a direction to permit the shaft to move in a direction away from the chute, the arms being positioned in advance of said slots.
3. A machine of the class described comprising a chute, said chute having side walls provided with slots, a shaft seated within said slots, feeding means carried by the shaft and positioned within the chute, means for 40 rotating the shaft, oppositely directed arms

pivotally supported by the chute, the inner extremities of said arms being provided with meshing teeth to cause said arms to rock in unison and in the same direction, links connecting the outer portions of the arms 50 and the shaft, said slots being disposed in a direction to permit the shaft to move in a direction away from the chute, and means for constantly urging the shaft in the opposite direction.

55

4. In a machine of the class described having a hopper provided with a discharge opening, an elongated arm pivotally supported intermediate its ends within the hopper and disposed toward the discharge opening, means for locking said arm, a head carried by the extremity of the arm adjacent to the discharge opening, and tines extending upwardly from said head and terminating in close proximity to and extending across the discharge opening.

60

5. In a machine of the class described having a hopper provided with a discharge opening, an elongated arm pivotally supported intermediate its ends within the hopper and disposed toward the discharge opening, means for locking said arm, a head carried by the extremity of the arm adjacent to the discharge opening, and tines extending upwardly from said head and terminating in close proximity to and extending across the discharge opening, said tines being provided with oppositely directed arms.

70

6. A machine of the class described having a hopper provided with a discharge opening, a vibratory member within the hopper, means for operating said member, tines extending upwardly from said member and terminating in close proximity to and bridging the discharge opening, said tines 75 being provided with oppositely directed arms.

75

In testimony whereof I hereunto affix my signature.

GOTTFRIED SCHICK.
